CHARLES KNAPP, OF MINNEAPOLIS, MINNESOTA.

AUTOMOBILE-LOCK.

1,391,390.

Specification of Letters Patent. Patented Sept. 20, 1921.

Application filed October 18, 1919. Serial No. 332,080.

To all whom it may concern:

Be it known that I, CHARLES KNAPP, a citizen of the United States, and a resident of Minneapolis, in the county of Hennepin and State of Minnesota, have invented certain new and useful Improvements in an Automobile-Lock, of which the following is a specification.

One object of my invention is to provide in an automobile lock means for locking directly onto the fly wheel of the engine.

Another object is to provide means for making the lock effective should the lock bolt be brought onto the locking means without being in perfect alinement therewith.

Another object is to provide improved means for holding the lock bolt into locked relation with its locking means.

With these and incidental objects in view, the invention consists of certain novel features of construction and combination of parts, the essential elements of which are hereinafter described with reference to the drawing which accompanies and forms a part of this specification.

In the drawing, Figure 1 is a fragmentary plan view of a transmission housing having my improved lock applied thereto; Fig. 2 is an enlarged sectional view taken on the line 2—2, Fig. 1; and Fig. 3 is an enlarged detail of a fragment of the lock bolt, with the two halves thereof separated.

As shown in Fig. 2, the fly wheel housing 1 has bolted or otherwise suitably fastened thereto a casing 2 with a gasket 3 therebetween.

A threaded bushing 4 and lock nut 5 form a closure for the lower end of the casing, 40 and slidably mounted in the bushing 4 and in the casing at 5' is a lock bolt 6, the end 7 of which is fashioned to closely nest with the gear teeth 8 on the fly wheel 9', as ordinarily provided for coöperation with an electric starting motor generator.

The upper end of the lock bolt is formed into a tongue 7', fitting in the slot 8' of the shaft 9, the pin 10 playing in the slot 11 of the tongue 7' so as to allow a vertical movement of the lock bolt.

The spring 12 positioned in the casing 2 abuts against the washer 13 supported by the pin 14 through the lock bolt 6 so the lock bolt is normally pressed downwardly in engagement with the gear teeth of the fly wheel.

With the spring controlled movement of the lock bolt as described, if the device should be locked as hereinafter described when the fly wheel stands in such a position that the tongue on the end of the bolt would rest on top of one of the gear teeth instead of nesting therewith, the spring 12 would force the tongue into its locked position with respect to the teeth, upon the first slight movement of the fly wheel, if anyone should attempt to start the engine.

The shaft 9 is threaded at 15 and engages with the nut 16, rotatable by means of the hand wheel 17. A key 18 inserted through the casing 2 and passing tangentially through the annular space 19 maintains the nut in a fixed vertical position so the turning of the nut will raise or lower the shaft 9. It is therefore evident that the rotation of the hand wheel 17 will draw the lock bolt 6 out of engagement with the teeth 8 if the shaft 9 is not locked by the lock 20 and the hand wheel 17 cannot be rotated if the vertical movement of the shaft 9 is prevented by the lock 20.

The lock 20 has a finger 21 rotatable by the key 22, and is so positioned with respect to the latch 23 that when the key is rotated in a counter-clockwise direction the finger 21 swings the latch downwardly out of engagement with the catch 24 and then engaging with the lock bar 25 at 26 retracts the bar from engagement with the shaft 9.

A lip 27 prevents the further rotation of the finger 21 and as the latch 23 now engages with catch 24 in its notch 28 the key cannot be withdrawn unless the device is again locked.

Inasmuch as the fly wheel 9' rotates in a counter-clockwise direction the tendency is for the gear teeth to force themselves into tighter engagement with the end 7 of the lock bolt 6, so the engine cannot be started against the locking of the lock bolt, as the spring 12, if comparatively light, will keep the lock bolt in a positive locked position in the gear teeth.

While I have described my invention and illustrated it in one particular design, I do not wish it understood that I limit myself to this construction, as it is evident that the application of the invention may be varied in many ways within the scope of the following claim:

Claim:
In an automobile lock the combination of

a casing, a lock bolt slidably mounted in said casing, a spring for holding said lock bolt in an extended position, a shaft joined to said lock bolt, but allowing a definite 5 slideable movement in relation thereto, rotatable means carried by said casing for lifting said shaft and thereby said lock bolt,

a lock including a bolt positioned in said casing, said bolt being engageable with said shaft, and means in said lock for withdrawing said bolt from engagement with said shaft. 10

CHARLES KNAPP.
